1 Claim. (Cl. 57—156)

This is a division of application Serial No. 223,710,
filed September 14, 1962, now abandoned.

The present invention concerns improvements in or
relating to processes for winding and doffing bobbins.

It is well known that during the winding of bobbins of
yarn for use, for instance, as warping yarn, the first turns
of yarn wound on to the bobbin are wound separately from
the main body of yarn in order to provide an available
“tail” of yarn for use in connecting the last length of yarn
to be withdrawn from the bobbin with the leading end of
yarn of another bobbin.

In order that the yarn at this tail end shall run freely
when the time comes for it to be withdrawn, it is im-
portant that the “tail” shall be comprised of properly-
spaced helical turns on the bobbin surface that will not
jam on withdrawal; and it is the main object of the inven-
tion to provide a process for winding and doffing bobbins
on a ring spindle apparatus that will ensure that a
“tail” is properly formed and secured in place at one end
of the bobbin.

According to the invention, yarn is wound on a bobbin
on a ring spindle apparatus, and the bobbin is doffed, by
a process comprising the steps of winding the initial
lengths of yarn on a waste spool spaced heightwise below
the bobbin, winding spaced turns of yarn in the form of a
helix on the lower end-portion of said bobbin, said turns
connecting the yarn on said waste spool with the main
build of yarn on the bobbin, completing the winding of
the main build of yarn, and doffing the bobbin by lifting
it upwardly of the spindle of the said ring spindle appa-
ratus so that yarn in the lower of said helical turns is auto-
matically trapped in a slot formed in a radial projection
from the surface of the bobbin or formed between the
projection and the surface of the bobbin itself, the line of
direction of said slot towards its open end being such as to
intersect the line of direction of yarn in said helical turns.

The invention employs a bobbin with yarn wound in a
package therein and having a transfer “tail” comprising
spaced helical turns on its lower end-portion, said helical
turns being secured by the lowermost one being trapped
in a slot formed in a radial projection from the surface
of the bobbin, or formed between the projection and the
surface of the bobbin itself.

The invention will now be described, for the purposes
of illustration only, with reference to the accompanying
drawings and in connection with the winding and doffing
of bobbins of synthetic yarn, such as nylon, immediately
after the drawing (stretching) operation.

In the drawings,

FIGURE 1 is a diagrammatic representation of appa-
ratus for drawing (stretching);

FIGURE 2, FIGURE 2A, and FIGURE 2B show the
manner in which projections can be formed at the base
of a plastic sleeve;

FIGURE 3 shows how projections can be made by the
use of plastic strips at the base of a bobbin;

FIGURE 4 shows how a projection can be made in
a rubber band at the base of a bobbin;

FIGURE 5 is a diagrammatic representation, partly in
section, of a ring spindle at the start of winding according
to the invention;

FIGURE 6 is a diagrammatic representation, partly
in section, of the lower portion of the apparatus of FIG-
URE 5, during a subsequent part of the winding;

FIGURE 7 is a diagrammatic representation, partly in
section, of the apparatus of FIGURE 6, at the comple-
tion of winding and at the start of doffing; and

FIGURE 8 shows how the transfer tail is trapped at
the base of the bobbin of FIGURE 7 on completion of
doffing.

The drawing (stretching) apparatus depicted in FIG-
URE 1 comprises a holder 1 for cake 3 of undrawn yarn,
yarn guide 5, tension bars 7, and traverse guide 9 for tra-
versing the undrawn yarn across feed roll 11. Nip roll 13,
acting in conjunction with feed roll 11, ensures that the un-
drawn yarn is forwarded positively. Snubbing pin 15 is
positioned intermediate the feed roll 11 and draw roll 17,
around the latter of which and separator roll 19, the yarn
is wound with a number of wraps. Thence, the drawn
yarn proceeds via balloon guide 21 to be wound up by
the ring spindle apparatus comprising rotatable spindle 23,
with waste spool 25 at the base thereof, whorl 27, around
which driving belt 29 is passed, and ring 31 held in holder
33 and around which traveller 35 rotates. The yarn is
wound in package 37 on a bobbin (not shown) affixed to
spindle 23.

It is explained that the initial lengths of yarn produced
at the start of winding will be either undrawn or incom-
pletely drawn, and these are the lengths which are
wound on the waste spool. Such winding is effected by
a lowering of the traveller ring, either individually or as
one of a number of such rings held by a ring rail, to below
its ordinary operating traverse range; and such ring is
slowly raised to operating position, once the drawing op-
eration has started to run smoothly, thus producing the
series of spaced helical turns connecting the yarn on the
waste spool with the yarn in the main build. The yarn
is then wound into the main build by traversing it in the
required manner along the main middle portion of the
bobbin; and when the required amount of yarn has been
so wound, the ring is lowered to the level of the waste
spool, the end of yarn is severed and winding ceases.
The spindle is then braked to bring it to rest for the doff-
ing of the bobbin which is carried out by lifting the bob-
bin vertically for a short distance, either by hand or with
the assistance of a defining tool, until it can be removed
from the spindle.

Although only one radial projection has been referred
to above, it is in fact preferred to use at least two of
them, to ensure that the helix of yarn is readily trapped;
and the actual form to be taken by a projection, apart
from the basic requirements that it shall project slightly
from the cylindrical periphery of the lower end-portion of
the bobbin and that the line of direction of the slot to-
wards its open end shall intersect the line of direction of
yarn in the helical turns, will depend on the type of
bobbin in use. For the most part, producers' bobbins
employed in the winding of synthetic yarns such as nylon
are cylindrical tubes without flanges; and they may be
composed of plastic or cardboard sleeves fitting closely
on a metal core, or of a metal tube itself. It is a rela-
tively simple matter to form or to cut projections in the
sleeves; but in the case of all-metal bobbins it is necessary
to fit a sleeve or band over the lower end-portion of the
bobbin, this sleeve or band having the projection or pro-
jections formed in it.

In connection with FIGURES 2-4, and considering
firstly bobbins composed of a plastic sleeve 39 and metal
core 41, it is possible to make the sleeve with the pro-
jection or projections 43 integral therewith and extend-

ing below the base thereof from its periphery. Such projections, as shown in FIGURES 2 and 2A, having a slot formed along the line of the periphery and half the width of the projection in length, can be raised slightly to stand out from the surface of the bobbin (FIGURE 2) or they can be bent right over upwardly (FIGURE 2A), the latter arrangement providing a more positive means for engagement with the helical coils 45. Alternatively, as shown in FIGURE 2B, V-shaped flaps 43 can be punched out of the base of the sleeve 39, with the apex of the V pointing upwardly and sideways so as to provide a slot into which the helical coil or coils will be drawn on doffing the bobbin. In yet another alternative, as shown in FIGURE 3, which can also be employed with cardboard sleeves, a small strip 47 of plastic material can be wedged between the sleeve 39 and the plastic cone-shaped fitting at the base of the metal core 41 so as to project below the end periphery of the sleeve, and this strip, having a slot cut through half its width along the line of the periphery, is then bent right over upwardly to form a projection 43 in the same way as described above for the integral projections.

For the all-metal bobbins, as well as for those consisting of a sleeve fitted on a metal core, a plastic sleeve can be pressed over the base of the bobbin, this sleeve having diagonal slots cut in one or two places around its upper periphery. It is possible, as shown in FIGURE 4, to use a stretched rubber band 49 or an expansible metal clip around the lower end-portion of the bobbin 41 instead of a plastic sleeve pressed over its base, the rubber band or metal clip having notches cut in its upper periphery in the same way as the plastic sleeve, to form projections 43 which stand out sideways from the band or clip.

The operation of the winding and doffing of a bobbin according to the invention is described with reference to FIGURES 5-8.

At the start of winding, as shown in FIGURE 5, the machine is threaded-up by passing the yarn round the feed and draw rolls (see FIGURE 1) through the guide 21 and traveller 35, and then the yarn is anchored by being wound around the spindle blade 23. The bobbin 41 is then loaded on to the spindle.

The machine is then started. The ring 31, which may be controlled by an automatic bunch winder, remains stationary long enough for the undrawn and off-standard yarn produced during startup to be wound on to the waste spool 25. The ring 31 is then raised and whilst rising it winds a spiral of yarn 45 over the waste spool 25 and the lower portion of the bobbin 41, as shown in FIGURE 6. At this time, the rubber band 49, with its projection 43 and its slot, is shielded by the wall of the waste spool 25, so that no yarn can come in contact with it. The ring rail then moves in a specified pattern of traverse motion, to produce the required type of package 37.

At the completion of winding, and whilst the machine is slowing down to rest, the ring 31 is lowered to the waste

spool position that it was in at the start of the winding operation. This lowering of the ring, as shown in FIGURE 7, causes a wide-angled helix 51 of yarn to be wound, firstly over the lower portion of the package 37, next over the helical turns 45 on the lower portion of the bobbin 41 and then over those turns on the waste spool 25.

To doff the bobbin (i.e. the bobbin 41 on which is wound yarn package 37) it is lifted upwardly along the spindle 23. This causes both the helical turns 45 and the wide-angled helical turns 51 to unwind somewhat and to slip where they are wound on the lower portion of the bobbin 41. The two spirals do, however, unwind in opposite directions. As shown in FIGURE 7, one turn of the spiral 45 becomes engaged with the outwardly-extending projection 43, enters the slot in the band 49 and is trapped therein. The turns of the wide-angled helix 51, unwinding in the opposite direction, slide over the projection 43 and do not enter the slot. The trapping of the yarn in the slot will be felt by the operative as he lifts the bobbin, and he knows that he can then cut the yarn in both spirals below the band 49. Thus, as shown in FIGURE 8, the end 51 is free and the end 45 is trapped in the slot. Such trapping of the end 45 in this manner is quite secure enough for the ordinary incidents of handling; and no other means is required to secure the helical turns in place. These turns, comprising a transfer "tail," are thus prepared on the ring spindle apparatus in the manner in which they are required for use in a subsequent textile operation such as warping.

What we claim is:

A process for winding yarn, and for doffing a yarn package so wound, on a ring spindle apparatus, comprising the steps of winding the initial lengths of yarn on a waste spool spaced heightwise below a bobbin, winding spaced turns of yarn in the form of a helix on the lower end-portion of said bobbin, said turns connecting the yarn on said waste spool with the main build of yarn on the bobbin, completing the winding of the main build of yarn, and doffing the bobbin by lifting it upwardly of the spindle of the said ring spindle apparatus so that yarn in the lower of said helical turns is automatically trapped in a slot formed by a radial projection from the surface of the bobbin, the line of direction of said slot towards its open end being such as to intersect the line of direction of yarn in said helical turns.
